KNITTING MACHINE

Earnest H. Scott, Burlington, N. C., assignor to
 Grace Hosiery Mills, Inc., Burlington, N. C., a
 corporation of North Carolina

Application April 23, 1938, Serial No. 203,721

15 Claims. (Cl. 66—135)

This invention relates to knitting machines and more particularly to a clocking or patterning attachment for knitting machines.

One object of the invention is the provision of an attachment for a circular knitting machine constructed and arranged to cooperate with the needles of the usual needle cylinder for incorporating into the stocking additional yarn, visible externally of the stocking for obtaining clocking or other stripe or patterns in such manner as to eliminate un-knit yarn portions on the inside of the stocking and the consequent necessity for cutting or otherwise removing such un-knit yarn from the stocking. More specifically, this object of the invention relates especially to circular knitting machines such as the well-known Scott & Williams type of seamless hosiery machine provided with a revolving needle cylinder and a dial plate and mechanism designed to cooperate in conjunction with the needles of the cylinder for forming the clocks. The machine of this type is known as the Scott & Williams HH spiral machine. The un-knit yarn portions referred to extend interiorly of the stocking from one line of clocks to the other and must subsequently be cut out, leaving sufficient portion of the uncut yarn for retaining the clocks. These loose ends are objectionable and furthermore the clocks are not securely fastened in position. In accordance with the present invention, and in fulfillment of the presently stated object thereof these objections as well as others are obviated and in addition an improved clocking or similar or other patterning may be obtained. The above objects of the invention and other objects will be fully understood from the following description considered with reference to the accompanying drawings. The invention will be shown and described as embodied in the above mentioned Scott & Williams HH spiral machine, it being understood that only sufficient parts of the machine necessary to the explanation of the invention will be illustrated, since such machines are well known. It is to be understood, however, that the machine is to comprise all the instrumentalities necessary for an operative circular knitting machine, without specific reference thereto other than to the parts hereinafter mentioned for the purpose of explaining the present invention.

50 In the drawings:

Fig. 1 is a rear view in elevation, with parts in section, of the head of a machine having the present invention embodied therein;

Fig. 2 is a side perspective view of the head of the machine;

Fig. 3 is a vertical sectional view, partly in elevation and parts being omitted for the sake of clearness in illustration;

Fig. 4 is a sectional-plan view on the line 4—4 of Fig. 1;

Fig. 5 is a plan view of the bobbin stand taken along the line 5—5 of Fig. 3;

Fig. 6 is a bottom plan view of the latch ring and certain parts carried thereby;

Fig. 7 is a detailed sectional view on the line 10—10 of Fig. 6;

Fig. 8 is a sectional view on the line 8—8 of Fig. 4;

Fig. 9 is a sectional view on the line 9—9 of Fig. 2;

Fig. 10 is a sectional-plan view on the line 10—10 of Fig. 3;

Fig. 11 is a detail sectional view on the line 11—11 of Fig. 10.

Referring now to the drawings in detail, it is seen that the invention is embodied in connection with a circular knitting machine having a revolving needle cylinder 10 provided with the usual latch needles 'N independently movable vertically at the upper end of the cylinder in 25 the customary grooves provided therein. The usual latch ring 12 is positioned over the top of the needle cylinder and is pivotally connected as by arms 14 to some stationary part of the machine frame as indicated at 16 in Fig. 2. Said 30 latch ring is provided with the usual gap 18 for the reception of the yarn guide fingers 19 (indicated generally in Fig. 2) and with the conventional flanged guard ring 20 which is rotatably mounted for selectively opening and closing 35 said gap. The shear plate 22 carries the usual yarn cutter and clamp 24 and pivoted yarn clamp 26 provided with a leaf spring 28 as shown in Figs. 1, 2, and 10. Said shear plate is supported in fixed position in relation to latch ring 12 by a rod 30 secured at its lower end to said shear plate and adjustably fixed as by a set screw 32 in bracket 34. Plate 22 is provided with a hub 36 which receives the lower end portion of stationary sleeve 38 carried by said bracket. The vertical shaft 40 is mounted for rotation in sleeve 38 and is splined to a beveled gear 42 operated by the bevel gear 44 fixed to rotary shaft 45 which is driven by shaft 46 actuated from the usual main drive shaft.

According to the present invention, as hereinbefore indicated, provision is made for incorporating yarn in the stocking for forming clocks or other patterning extending vertically of the stocking. The mechanism provided for that pur-

50

55

pose and forming a part of the above described mechanism will now be considered first, with particular reference to Figs. 1 and 3 of the drawings. As here shown, the clocking mechanism comprises a tube 50 journalled for rotation in a stationary sleeve 52. Said tube is provided at its lower end with a plurality of, here shown as two, yarn guiding fingers constituted by narrow tubes through which the yarn passes outwardly from the interior of tube 50. Said yarn guiding fingers are positioned for rotation close to the inner periphery of latch ring 12 for feeding yarn to the needles N when the latter are raised for this purpose, it being understood that the pattern of the clocks or other design elements formed by the yarn supplied by fingers 54 will depend upon the needles raised in position to receive said yarn, the raising of appropriate needles being accomplished by any suitable mechanism as that provided heretofore in circular knitting machines of the type described herein. Yarn fingers 54 have a circular path which extends into groove 55 of the latch ring. Said groove receives and guides the guard ring 20 for opening and closing the gap 18 and is itself conventionally provided with a gap 59 through which fingers 54 can move into groove 55. When the gap 59 in ring 20 is thus positioned to permit entry of fingers 54 into groove 55, the ring is positioned for opening gap 18. When the ring 20 is positioned to close gap 18, the gap in the ring is out of registry with fingers 54 and the latter are prevented, by the portion of the ring adjacent its gap, from entering groove 55, but at that time the fingers are in retracted stationary position as will hereinafter be explained. Thus, yarn fingers 54 are rotated adjacent the needle circle. Said fingers 54 rotate at such speed in relation to the needles N that one of said yarn fingers supplies yarn to the needles for forming the clocks at one side of the stocking while the other of said yarn fingers supplies yarn for forming the clocks at the opposite side of the stocking, whereby the clocks at one side of the stocking are independent of the clocks at the other side of the stocking thereby eliminating connecting or floating thread portions extending from one line of clocks at one side of the stocking to the line of clocks at the other side of the stocking which in certain machines of the prior art were unknit and were required to be cut from the stocking as hereinbefore explained. On the other hand the clocks thus knit into the stocking are firmly retained therein and loose ends of yarn or threads are eliminated.

The mechanism for rotating tube 50 which carries yarn guide fingers 54 will now be described. Tube 50 is fixed to and depends from the bobbin stand plate 56, centrally thereof, by means of a sleeve 57 fastened to said plate and to said tube. There is a releasable driving connection between plate 56 and a gear 58 constituted by a projection 60 depending from the lower surface of plate 56 for engagement by a projection 62 fixed to a plate 64 fastened as by a set screw 66 to gear 58. Gear 58 rests on a shelf 70 fixed to bracket 72 (Fig. 4) and rotates on said shelf about inner ring 74 fixed to the shelf by a pin 76 in position around sleeve 57. Upward movement of gear 58 and annular plate 64 is prevented by a retaining washer 78 which overlies the inner top marginal edge portion of the top of gear 58 within annular plate 64. Retaining washer 78 is fixed by pin 76. It will be observed that projection 60 on plate 56 and projection 62 on plate 64

provide a releasable one way clutch for driving bobbin stand plate 56. As shown in Fig. 4 gear 58 is driven from shaft 40 by gears 80 and 82. Gear 80 is fastened to the upper end of shaft 40 by a sleeve 84 integral with or otherwise fixed to said gear. Intermediate gear 82 transmits the motion of gear 80 to gear 58 and is mounted for rotation on plate 70 about the shank of a pivot screw 86 which holds said gear removable in position on said plate and in mesh with gear 58. 10

In accordance with the present invention, provision is made for raising the yarn fingers 54 upwardly away from the needles automatically when the needles are raised for knitting the heel and toe portions of the stocking, such raising of needles taking place in the Scott & Williams knitting machine with which the clocking or patterning attachment of the present invention is embodied as illustrated herein. Provision is also made for interrupting the rotation of the bobbin standard of yarn fingers 54 in the raised position of the latter. In order to permit said yarn fingers to be raised tube 50 is mounted for longitudinal movement in sleeve 52 and ring 74 on plate 70. A spring 88 bears at one end on the lower enlarged portion 90 of tube 50 and at its other end on the end 92 of sleeve 52, and therefore resiliently opposes upward movement of tube 50 and yarn fingers 54 carried thereby. It will be understood that when tube 50 is moved to raise the yarn fingers 54 above the needles when the latter are operative to knit the heel and toe portions of the stocking, bobbin stand plate 56 is raised, and clutch elements 60 and 62 are thereby automatically disengaged for interrupting the driving connection between said elements. For more quickly arresting the motion of tube 50 and of the bobbin stand when the latter is disengaged from its driving connection, there is provided a brake member 94 provided with a friction shoe 96 which is in engagement with tube 50 within sleeve 52. Said brake 94 is positioned within tubular extension 98 of sleeve 52. An adjustable screw 99 is threaded into the outer end of tubular extension 98 for adjusting the friction of the brake on tube 50. It will be understood that the friction of said shoe 96 is insufficient to impede the rotation of said tube when the latter is driven, but in view of the light weight of said tube and associated parts said friction shoe is effective to quickly stop the rotation of said tube and of the bobbin stand when the driving connection of the stand is disengaged. 35

The means for automatically raising bobbin stand plate 56 comprises a roller 100 carried at one end of a lever 102 which is pivoted intermediate its ends on a pivot screw 104 secured to a bracket extension plate 106. Outer end of pivoted lever 102 is provided with a fixed upwardly extending arm 108. Lever 102 is operated by a pivoted lever 110 connected by a link 112 to the upper end of arm 108. Lever 110 is pivoted intermediate its ends, as at 114, to some stationary part of the knitting machine in position to be engaged at its lower end 116 by a cam on the main drum 120 of the machine. It will be understood that lever 110 is controlled by drum 120 for lowering and raising bobbin stand plate 56 and tube 50 at the appropriate times in the course of knitting the stocking thereby to project and retract 70 yarn fingers 54, said yarn fingers effective or ineffective to supply yarn to the needles, as may be necessary in the course of the automatic operation of the machine for making a stocking.

As shown more clearly in Figs. 1 and 6, there is 75

provided a curved yarn guard bar 122 disposed in the latch ring between the inner periphery of the latter and the outer edge of shear plate 22, for preventing the needles from tangling with the 5 yarn supplied to the knit web by yarn fingers 54. Guard bar 122 is fixed to a part 124 of the bracket 34 by a vertically extending bar portion 126 fastened to said bracket part 124 in any suitable way as by screws 128 (Fig. 7). There is also provided a yarn guard pin 134 positioned between bar 122 and the edge of plate 22, for guiding the 10 yarn fed by fingers 54 and attached to the web below the shear plate 22, said yarn engaging pin 134 between said pin and guard bar 122. Provision is made for retracting pin 134 when yarn 15 fingers 54 are raised to retracted position. For this purpose pin 134 is formed as part of an L-shaped member 136 pivoted at its end 138 remote from the yarn-engaging end of said guard pin 20 on a bracket extension plate 140 by means of a pivot screw 142 (Fig. 1). Member 136 is connected to lever 102 by means of an adjustable sectional link 144 comprising a part 146 pivotally connected at its lower end to member 136 and a part 148 25 pivotally connected at its upper end by means of a pivot screw 150 to lever 102. As shown in Fig. 8, parts 146 and 148 of sectional link 144 have an adjustable slot and pin connection 152 whereby said link 144 can be shortened or lengthened as 30 may be necessary or desirable. When pin 134 is raised, that is when yarn fingers 54 are retracted, the yarn supplied by said fingers and connected to the knit web, passes over plate 22, as the needle cylinder rotates, and is engaged by spring 28 of 35 clamp 26 and cut from the web by cutter 24. As shown in Figs. 10 and 11, plate 22 has a bevelled edge portion 153 for guiding the yarn into engagement with said clamps and cutter.

Referring now to the bobbin stand hereinbefore mentioned in connection with plate 56 thereof, it will be observed that the yarn bobbins B are carried by plate 56, being removably secured for rotation thereby on pins 154 fixed to and up-standing from said plate. Suitable yarn tensioning and take-up means for the yarn from each of said bobbins supplied to the yarn fingers 54 are provided on plate 56. As here shown, there are two vertically disposed rods 156, each provided with a lower foot portion 158 for securement to the upper surface of plate 56, screws 160 being provided for this purpose. A yarn guide hook 162 is removably secured by said screw 160 to the foot portion 158 of each rod 156. Each rod 156 is provided with slot 164 extending longitudinally 40 of said rod for the major portion of its length and transversely of said rod for the full width thereof. A yarn take-up sleeve 166 provided with a transverse aperture 168 is movable longitudinally on each rod 156 in engagement with a light spring 45 170 surrounding the rod. Spring 170 opposes downward movement of sleeve 166 and resiliently urges sleeve 166 toward the top of the rod. A yarn tensioning device 172 is removably secured to the top of each rod 156 by a set screw 174. It 50 will be understood that the yarn Y as it leaves its bobbin is engaged by the spring-pressed plate 176 of its companion tensioning device 172 and passes through an opening 178 (Fig. 9) in block 55 180 by which the tensioning device is fastened to rod 156. The yarn passing through opening 178 extends downwardly and is engaged with the guide hook 162 on its companion rod 156, and then it extends upwardly and passes through the 60 aperture 168 in sleeve 166 and through the slot 164 in rod 156 from one side of said rod to the 65

other end, and finally the yarn extends downwardly into one of the openings 182 in disc 184, which is fixed in the top of plate 56, for passage through tube 50 and through yarn fingers 54. 70 Rods 56 and slots 164 are long enough to permit downward movement of take-up sleeves 166 during approximately one-half revolution of needle cylinder 10 without withdrawing yarn from the bobbins, that is during the movement of the needles from the side of cylinder at which yarn 75 fingers 54 are located and to which yarn is supplied to said needles by said finger to a diametrically opposed point in the circular path of the needles. During approximately the other half of the revolution of the needle cylinder take-up sleeves 166 move upwardly thereby taking up the slack in the yarn. It will be understood that as the yarns supplied by the needles 54 are knit into the web the tension of the spring on the take-up sleeves increases sufficiently thereby to 80 tension the yarn for withdrawing the necessary amount of yarn from the bobbins through the companion tensioning device 172.

Thus it is seen that the constructions herein shown or described are well adapted to accomplish the several objects of the present invention. It will be understood, however, that the invention may be embodied otherwise than as here shown and that in the forms of the invention herein disclosed, certain changes in the construction and 85 arrangement of parts may be made and will readily occur to skilled artisans, particularly in view of the present disclosure. Therefore I do not wish to be limited precisely to the construction herein shown or described, except as may be required within the scope of the appended claims.

Having thus described my invention, what I claim and desire to secure by Letters Patent is:

1. In a circular knitting machine having a rotatable needle cylinder, a bobbin stand mounted 40 for rotation about an axis parallel to the axis of said needle cylinder, yarn guides mounted for rotation with said bobbin stand for supplying yarn from said bobbins to the needles of said cylinder, said yarn guides being positioned to rotate adjacent the needle circle and mounted for longitudinal movement in a direction parallel to the axis of the needle cylinder, for projection and retraction in relation to the needles for supplying yarn to and withholding yarn from said 45 needles, a releasable driving connection for said bobbin stand for rotating the latter in timed relation to the rotation of said needle cylinder, and means for projecting and retracting said yarn guides and for disengaging said bobbin stand 50 from said driving connection when said rotary yarn guides are retracted.

2. In a circular knitting machine having a rotatable needle cylinder, a bobbin stand mounted for rotation about an axis parallel to the axis of 60 said needle cylinder thereabove, yarn guides mounted for rotation with said bobbin stand for supplying yarn from said bobbins to the needles of said cylinder, a rotary shaft extending transversely of said cylinder thereabove, a longitudinal shaft driven by said transverse shaft, a releasable driving connection between said bobbin stand and said longitudinal shaft for rotating said bobbin stand and yarn guides in timed relation to the rotation of said needle cylinder, and 65 means for releasing said connection to interrupt the rotation of said stand and yarn guides while said needle cylinder continues to rotate.

3. In a circular knitting machine having a rotatable needle cylinder, a bobbin stand mounted 70

for rotation about an axis parallel to the axis of said needle cylinder thereabove, yarn guides mounted for rotation with said bobbin stand for supplying yarn from said bobbins to the needles of said cylinder, said yarn guides being positioned to rotate adjacent the needle circle, a rotary shaft extending transversely of said cylinder and positioned thereabove, a longitudinal shaft driven by said transverse shaft, a releasable driving connection between said longitudinal driven shaft and said bobbin stand for rotating said bobbin stand and yarn guides in timed relation to the rotation of said needle cylinder, and means for releasing said connection to interrupt the rotation of said stand and yarn guides while said needle cylinder continues to rotate.

4. In a circular knitting machine having a rotatable needle cylinder, a bobbin stand mounted for rotation about an axis extending longitudinally of said needle cylinder, yarn guides mounted for rotation with said bobbin stand for supplying yarn from said bobbins to the needles of said cylinder, said yarn guides being positioned to rotate adjacent the needle circle and mounted for longitudinal movement in a direction parallel to the axis of the needle cylinder, for projection and retraction in relation to the needles for supplying yarn to and withholding yarn from said needles, a releasable driving connection for said bobbin stand for rotating the latter in timed relation to the rotation of said needle cylinder, and means for projecting and retracting said yarn guides and for disengaging said bobbin stand from said driving connection when said rotary yarn guides are retracted.

5. In a circular knitting machine having a rotatable needle cylinder, yarn guides for supplying yarn for incorporation into the knit web at points spaced circumferentially of the web, a shear plate having a yarn clamp and cutter, said shear plate being mounted within the needle circle, a stationary yarn-guard bar spaced from the outer edge of said shear plate between the latter and the needle circle and extending circumferentially of said plate, means for guiding the yarn, knit into the web and supplied from said fingers, for movement, as the knit web rotates, between said bar and said plate and then below said plate, and means for retracting said last mentioned means to permit said web attached yarn to move over said plate for engagement by said clamp and cutter.

6. In a circular knitting machine having a rotatable needle cylinder, yarn guides for supplying yarn for incorporation into the knit web at points spaced circumferentially of the web, a shear plate having a yarn clamp and cutter, said shear plate being mounted within the needle circle, a stationary yarn-guard bar spaced from the outer edge of said shear plate between the latter and the needle circle and extending circumferentially of said plate, means for guiding the yarn, knit into the web and supplied from said fingers, for movement, as the knit web rotates, between said bar and said plate and then below said plate, and means for retracting said last mentioned means to permit said web attached yarn to move over said plate for engagement by said clamp and cutter, said plate having a bevelled edge portion for directing the yarn over the plate when said last mentioned means is retracted.

7. In a circular knitting machine having a rotatable needle cylinder, a bobbin stand mounted for rotation, yarn guides carried by said bobbin stand and positioned for rotation about an axis

parallel to the axis of said needle cylinder and adjacent the needle circle, said bobbin stand and said yarn guides being movable longitudinally in a direction parallel to the cylinder axis toward and away from the cylinder needles for projecting and retracting said yarn guides in relation to said needles for supplying yarn to and withholding yarn from said needles, means for rotating said bobbin stand and said yarn guides carried thereby operative when said yarn guides are in projected position, and means for moving said bobbin stand in a direction away from said cylinder needles thereby to move said yarn guides to retracted position and to render said rotating means ineffective to rotate said bobbin stand and said yarn guides.

8. In a circular knitting machine having a rotatable needle cylinder, a bobbin stand mounted for rotation, yarn guides mounted for rotation about an axis parallel to the axis of said needle cylinder and movable in a direction parallel to said axis for projection and retraction in relation to the cylinder needles for supplying yarn to and withholding yarn from said needles, said yarn guides being supplied with yarn from said bobbin stand, means for rotating said bobbin stand and said yarn guides comprising companion driving and driven members, said bobbin stand being movable to disengage said driving and driven members from each other to render said rotating means ineffective, and means for moving said yarn guides to retracted position and for moving said bobbin stand to disengage said driving and driven members.

9. In a circular knitting machine having a rotatable needle cylinder, a bobbin stand mounted for rotation, yarn guides carried by said bobbin stand and positioned for rotation about an axis parallel to the axis of said needle cylinder and adjacent the needle circle, said bobbin stand and said yarn guides being movable longitudinally in a direction parallel to the cylinder axis toward and away from the cylinder needles for projecting and retracting said yarn guides in relation to said needles for supplying yarn to and withholding yarn from said needles, means for rotating said bobbin stand and said yarn guides carried thereby operative when said yarn guides are in projected position, said rotating means including a shaft mounted for rotation in position over said cylinder and including also a releasable driving connection between said shaft and said bobbin stand, said driving connection being released when said bobbin stand is moved away from said cylinder needles, and means for moving said bobbin stand away from said cylinder needles thereby to move said yarn guides to retracted position and to release said driving connection between said shaft and said bobbin stand.

10. In a circular knitting machine having a rotatable needle cylinder and a pivoted latch ring, a rotary shaft extending longitudinally of said cylinder concentrically with the cylinder axis, a shaft carried by said latch ring and extending transversely of said cylinder thereabove, said transverse shaft having a driving connection with said longitudinal shaft for rotating the latter, means for feeding main yarn to the cylinder needles for forming a knit web, and means supported on said latch ring for feeding supplementary patterning yarn to said cylinder needles at points spaced circumferentially of the knit web, said means for feeding the patterning yarn comprising yarn guides mounted for rotation about an axis eccentric to the axis of said longi- 75

- 5   longitudinal shaft and in a circular path adjacent one side of the needle circle, and means including said longitudinal shaft for rotating said yarn guides whereby the patterning yarn supplied to the needles by one of said guides and incorporated into the knit web at one of said points is separate from the patterning yarn supplied by another of said guides and incorporated by the needles into the web at another of said spaced points.
- 10   11. In a circular knitting machine having a rotatable needle cylinder and a pivoted latch ring, a rotary shaft extending longitudinally of said cylinder concentrically with the cylinder axis, a shaft carried by said latch ring and extending transversely of said cylinder thereabove, said transverse shaft having a driving connection with said longitudinal shaft for rotating the latter, means for feeding main yarn to the cylinder needles for forming a knit web, a rotary bobbin stand supported on said latch ring, means supplied with yarn from said bobbin stand for feeding supplementary patterning yarn to said cylinder needles at points spaced circumferentially of the knit web, said means for feeding the patterning yarn comprising yarn guides mounted for rotation in a circular path adjacent one side of the needle circle, and means including said longitudinal shaft for rotating said bobbin stand and for simultaneously rotating said yarn guides whereby the patterning yarn supplied to the needles by one of said guides and incorporated into the knit web at one of said points is separate from the patterning yarn supplied by another of said guides and incorporated by the needles into the web at another of said spaced points, said yarn guides being movable to retracted position to interrupt the supply of patterning yarn to said needles during a predetermined operation of the needles for forming a portion of said web, a releasable driving connection between said longitudinal shaft and said bobbin stand, and means for releasing said driving connection to interrupt the rotation of said bobbin stand when said yarn guides are moved to retracted position.
- 15   12. In a circular knitting machine having a rotatable needle cylinder and a pivoted latch ring, a rotary shaft extending longitudinally of said cylinder, a shaft carried by said latch ring and extending transversely of said cylinder thereabove, said transverse shaft having a driving connection with said longitudinal shaft for rotating the latter, means for feeding main yarn to the cylinder needles for forming a knit web, a rotary bobbin stand supported on said latch ring, means carried by said bobbin stand and supplied with yarn therefrom for feeding supplementary patterning yarn to said cylinder needles at points spaced circumferentially of the knit web, said means for feeding the patterning yarn comprising yarn guides mounted for rotation in a circular path adjacent one side of the needle circle, and means including said longitudinal shaft for rotating said bobbin stand and for simultaneously rotating said yarn guides whereby the patterning yarn supplied to the needles by one of said guides and incorporated into the knit web at one of said points is separate from the patterning yarn supplied by another of said guides and incorporated by the needles into the web at another of said spaced points.
- 20   13. In a circular knitting machine having a rotatable needle cylinder and a pivoted latch ring, a rotary shaft extending longitudinally of said cylinder concentrically with the cylinder axis, a shaft carried by said latch ring and extending transversely of said cylinder thereabove, said transverse shaft having a driving connection with said longitudinal shaft for rotating the latter, means for feeding main yarn to the cylinder needles for forming a knit web, a rotary bobbin stand supported on said latch ring, means supplied with yarn from said bobbin stand for feeding supplementary patterning yarn to said cylinder needles at points spaced circumferentially of the knit web, said means for feeding the patterning yarn comprising yarn guides mounted for rotation about an axis eccentric to the axis of said longitudinal shaft and in a circular path adjacent one side of the needle circle, and means including said longitudinal shaft for rotating said bobbin stand and for simultaneously rotating said yarn guides whereby the patterning yarn supplied to the needles by one of said guides and incorporated into the knit web at one of said points is separate from the patterning yarn supplied by another of said guides and incorporated by the needles into the web at another of said spaced points.
- 25   14. In a circular knitting machine having a rotatable needle cylinder and a pivoted latch ring, a rotary shaft extending longitudinally of said cylinder, a shaft carried by said latch ring and extending transversely of said cylinder thereabove, said transverse shaft having a driving connection with said longitudinal shaft for rotating the latter, means for feeding main yarn to the cylinder needles for forming a knit web, a rotary bobbin stand supported on said latch ring, means carried by said bobbin stand and supplied with yarn therefrom for feeding supplementary patterning yarn to said cylinder needles at points spaced circumferentially of the knit web, said means for feeding the patterning yarn comprising yarn guides mounted for rotation in a circular path adjacent one side of the needle circle, and means including said longitudinal shaft for rotating said bobbin stand and for simultaneously rotating said yarn guides whereby the patterning yarn supplied to the needles by one of said guides and incorporated into the knit web at one of said points is separate from the patterning yarn supplied by another of said guides and incorporated by the needles into the web at another of said spaced points, said yarn guides being movable to retracted position to interrupt the supply of patterning yarn to said needles during a predetermined operation of the needles for forming a portion of said web, a releasable driving connection between said longitudinal shaft and said bobbin stand, and means for releasing said driving connection to interrupt the rotation of said bobbin stand when said yarn guides are moved to retracted position.
- 30   15. In a circular knitting machine having a rotatable needle cylinder and a pivoted latch ring, means for feeding main yarn to the cylinder needles for forming a knit web, and means supported on said latch ring for feeding supplementary patterning yarn to said cylinder needles at points spaced circumferentially of the knit web, said means for feeding the patterning yarn comprising a rotary bobbin stand supported on said latch ring, a tube fixed to and depending from said bobbin stand, yarn guides carried by said tube and rotatable thereby in a fixed circular

path adjacent one side of the needle circle, the yarn being supplied to said guides through said tube, said bobbin stand and yarn guides being movable rectilinearly as a unit in opposite directions to retracted and projected positions, respectively, for supplying yarn to and for withholding yarn from the cylinder needles, means

for moving said bobbin stand rectilinearly thereby to move said yarn guides to said retracted and projected positions, respectively, and means for rotating said bobbin stand thereby to rotate said tube and said yarn guides.

EARNEST H. SCOTT.
